UNITED STATES PATENT OFFICE.

FREDERICK JAMES TRUMPOUR, OF FOREST GLEN, MARYLAND.

BLUE-PRINTING MACHINE.

Application filed July 21, 1926. Serial No. 124,046.

The present invention relates to improvements in blue-printing machines and has for an object to provide an improved machine which will provide for the printing upon both sides of the sensitized blue-print paper in one passage of the paper through the machine.

Another object of the invention resides in providing a simple, compact and inexpensive machine, wherein this duplex printing upon both sides of the blue-print paper may be carried on cheaply and expeditiously.

The invention also contemplates the use of the machine for single printing upon one side only of the blue-print paper.

With the foregoing and other objects in view, the invention will be more fully described hereinafter, and will be more particularly pointed out in the claims appended hereto.

In the drawings, wherein like symbols refer to like or corresponding parts throughout the several views,

Fig. 1 is a side elevation of an improved blue-printing machine constructed according to the present invention.

Fig. 2 is a vertical section taken on the line 2—2 in Fig. 1.

Fig. 3 is also a vertical section taken on the line 3—3 in Fig. 2.

Fig. 4 is a fragmentary horizontal section taken on an enlarged scale through the feeding apparatus.

Fig. 5 is a vertical section through the same apparatus on the line 5—5 in Fig. 4.

Fig. 6 is a vertical section taken on the line 6—6 in Fig. 5.

Fig. 7 is an enlarged fragmentary section taken through a portion of the tracing clamping device.

Fig. 8 is a similar view taken along the line 8—8 in Fig. 7.

Fig. 9 is a cross-section taken on the line 9—9 in Fig. 8, with the clamp mechanism in the closed position.

Fig. 10 is a similar view showing the clamp open; and

Fig. 11 is a fragmentary section taken on the line 11—11 in Fig. 5, showing registering bars engaged with means for releasing the tracings.

Figure 12 is an enlarged sectional view of one of the socket members showing the spring.

Referring more particularly to the drawings, 12 designates generally the framework

of the machine, which framework may be of metal or any appropriate material shaped and constructed to carry the two exposure stations and the apparatus for feeding the sensitized blue-print paper and the two negatives or tracings past such stations.

The movement for passing the blue-print paper and negatives through the machine is derived from any appropriate source; for instance, from the electric motor 13 shown as installed in the base of the frame 12. The motor shaft 14 may be provided with the worm 15 meshing with the worm wheel 16. In Fig. 3 this worm wheel is shown as mounted fast upon a transverse shaft 17 journaled in appropriate bearings in the framework and having thereon also the beveled pinion 18 disposed in mesh with a similar pinion 19 upon the vertical transmission shaft 20. This shaft 20 extends up along one side of the framework and is provided with appropriate beveled gearing for communicating motion to the various feed and transmission belts as hereinafter described.

In Fig. 2 is shown as extending from one side of the frame an assembly table 21 carried upon an extension frame 22 which also supports the sprockets 23 and 24 for the pair of upper feed chains 25; and the other pair of sprockets 26 and 27 for the pair of lower feed chains 28. The adjacent runs of these feed chains pass above the assembly table 21 and these feed chains each carry a negative or tracing clamp bar to which an end of each tracing is secured for the purpose of initially drawing the tracing into the machine. At the inner end of the assembly table 21 is placed a casing 29 for containing the roll 30 of blue-print paper contained upon the shaft 31 from which it is unwound and passed outwardly through the slot 32. The adjacent runs of the upper and lower feed chains are adapted to pass respectively above and below this casing 29 and the upper run of the lower feed chain is required to pass through a trough made by the lower portion of the cylindrical casing 29 and an apron 33 extending from the inner end of the assembly table 21 and adjacent to the curved feed or contact table 34.

The blue-print paper is drawn out through the slot 32, as shown in Fig. 5, and in between the tracings or negatives conveyed along by the clamping device on the upper and lower feed chains. The three super-

posed films or webs are pressed tightly against the contact or feed table 34 and are advanced along such table 34 by means of upper and lower feed belts 35 and 36, the 5 adjacent runs of which pass above the curved contact table 34, in contact with each other and with the curved table. These feed belts 35 and 36 are narrower than the space between the pairs of feed chains, as indicated 10 in Fig. 4, in order to allow ample space at the sides of the feed belts for the placement of adjacent mechanisms. The upper feed belt 35 is carried upon the rollers 37 and 38; while the lower feed belt 36 is trained over 15 similar rollers 39 and 40. The lower rollers 39 and 40 are mounted in the fixed spindles or shafts 41 and 42 journaled in the side plates 43 of the framework while the upper rollers 37 and 38 are mounted upon 20 the shafts 44 and 45 extending through the slots 46 in the side plates 43, such slots extending vertically whereby the upper rollers 37 and 38 may be lifted away from the respective rollers 39 and 40 of the lower feed 25 mechanism. This separating movement of the several rolls and the belts is necessary to permit the clamping bars carrying the tracings or negatives past such feed mechanism. In order to accomplish the lifting 30 of the outer feeding roller 38, a pair of dogs 47 having wedge or cam upper surfaces disposed beneath the shaft 45 are provided, such dogs being pivotally hung upon the rod 48. The dogs are in position to be 35 engaged as to their under edges by the clamp bars as they pass downwardly toward the feed belts. In Fig. 2 the dogs and the roller 38 are shown in the lower position; while in Fig. 5 the parts are shown in the raised 40 position without clamp bars between the rollers 38 and 40.

These clamp bars are shown more particularly in Figs. 7 to 10, inclusive, and they are formed with the central cores 49 and 45 outer shells or casings 50. Both the cores and shells are formed with complementary depressions and crests 51 and 52 preferably on the under sides thereof and these cores and shells are shiftable axially where- 50 by to cause the depressed portions of the shell to ride outwardly on the crests of the bars. This causes the clamp jaws 53 and 54 to open as shown in Fig. 10. When the parts are restored to the positions shown in 55 Figs. 8 and 9, wherein the depressions of the shells or casings lie in the depressions of the bars, the clamp jaws 53 and 54 are closed. The end or other portion of a negative or a tracing is adapted to be clamped 60 by the jaws 53 and 54, the jaws being initially opened by the method above described for receiving same. The opening of the jaws may be either automatic or by hand, but provision for automatically opening the jaws at a later stage in the machine must be provided for and to this end the casing or shell 50, which casing extends completely across the space between the rollers 38 and 40 is made stationary while the cores are movable axially therein. There are two 70 cores in each shell, separated by the space at the center, as shown in Fig. 6 and these cores are adapted to be drawn outwardly by cam or abutment plates 68 as presently described in order to open the clamp jaws. 75 The outer end portions of each core 49 is provided with a reduced rounded portion 56 to which is secured a set collar 57 as by the use of a set screw 58. Adjacent the set collar 57 is a head 55 provided with a reduced portion 59 for fitting within and closing the outer end of the casing or shell 50. The head and casing are made fast. It is understood that the same type of head is provided to close the opposite end of the casing or shell. 80

The two cores within each of the shells are provided with outer terminal squared portions 60 adapted to fit into sockets 61 carried by the feed chains 25 and 28. These sockets project laterally and inwardly from the chains and it is preferred to supply each link of the chain with such a socket in order that the clamp bars may be selectively attached at any desired point along the chain. The sockets 61 are provided with three walls (Figs. 5 and 12) for engaging three sides of the squared terminal end 60 of the core but one side of the socket is left open to receive such terminal end 60 and in order to maintain the terminal end in the socket, a flat spring 62 is secured as by the set screws 62' to one side of the socket and has its free ends overlapping the open side of the socket and preferably flared outwardly as at 300, Fig. 12, in order to admit of prying apart to admit the terminal end 60. These free ends of the spring yieldably retain the terminal ends 60 in the socket. The terminal end 60 of the core is adapted to slide axially in the socket and to be normally held projected by the coil spring 63 which is fitted in the innermost portion of the socket. The socket end is closed by the screw 1 plug 64 by means of which access may be had to the socket for removing the spring. The other end of the spring is adapted to receive the pin 65 for abutting directly against the end of the core terminal 60. The socket may be constituted of one of the pin connections of the chain link or it may be another portion of the chain as desired. 1

Referring to Fig. 4, it will be apparent that the set collar 57 is provided with a forwardly inclined curved or cam nose 66 positioned to engage with the forwardly inclined or cam edge 67 of an abutment or cam wall 68 mounted at each end of the inner feed rollers 37 and 39. As shown in Fig. 11 the cam or abutment plate 68 is

supported from the side wall 43 of the extension frame by means of the web 69 extending horizontally from the wall 43. The wall 43 is also provided with the spaced 5 horizontally extending guides 70 and 71 for receiving the chain links and for guiding the chain in its movements. The abutment plate 68 is provided upon its inner side with a flat abutment surface 72 for receiving the 0 outer end of the head 55 of the casing or shell for the clamp bar in order to hold the casing against movement while the core within is shifted axially by reason of the engagement of the cam set collar 57 with 5 the inclined surface 67 of the cam or abutment wall. When the set collar 57 is behind the abutment or cam wall, the pressed portions of the core have been moved over against the inner depressed portions of the 10 shell and consequently the clamp jaws 53 and 54, which have been lately holding the tracings or negatives are opened and the tracings or negatives are released. This operation is essential as the clamp bars and 15 shell turn about the sprockets 23 and 26 and return in the opposite direction upon the outer runs of the feed chains; while the blue-print paper and superposed and underlaid tracings are required to pass on to the 20 first exposure station.

The abutment wall 68, as shown in Fig. 5, is also provided with the divergent flaring ends 73 and 74 for the purpose of deflecting the clamp bars in opposite directions about 25 the sprockets 23 and 26. The lower clamp bar is designed to strike a cam lever 75 as it passes about the sprocket 26, the arm of such cam lever extending across this path of movement and the lever being fulcrumed 30 as indicated at 76 on an appropriate support. The lever will therefore be swung about in a counter-clockwise direction. This same movement causes a pull to the left to be exerted upon the rod 77 provided 35 at one end to the cam lever 75 and at its other end to the arm 78 upon the sliding feed plate 79 having one end arranged above the contact or feed table 34 and which plate 40 79 extends between the feed belts 35 and 36 and resting upon the latter, between the rollers 37 and 39. A coil spring 80 is attached to a fixed part and to the arm 78 for normally holding the feed plate 79 in the 45 normal position shown in Fig. 5. The inner edge of this feed plate is adapted to stop short of the rotary path that the clamp bar is required to take in passing about the lower sprocket 26, but as soon as this clamp bar has passed through the gap provided 50 by the end of this feed plate 79, the clamp bar strikes the lever 75 and causes consequent shifting of the plate 79 inwardly to close the gap between this same plate 79 and the bridging plate 81 disposed between the feeding 55 apparatus and the belt 82 which extends

about the first blue-printing or exposure station. It will be understood that the feed plate 79 is narrower in width than the distance between the pair of abutment or cam walls 68 and consequently these cam walls 70 will not interfere with the backward and forward shifting movement of the plate 79 as just described. The upper clamp bar, passing along beneath the lower run of the 75 upper feed belt 35, will, as it approaches the roller 37, lift this roller to permit passage of the clamp bar between the rollers 37 and 39 permitting the clamp bar to move on its way up about the sprocket 23.

A yoke 83 is provided in conjunction with the feeding apparatus, such yoke adapted to have a vertical sliding movement given it through the link 84 and the lever handle 85 fulcrumed upon an appropriate part of the framework. The yoke arms 86 and 87 engage below the arms 88 and 89 which are pivoted at the central point 90. These arms are coupled to the shafts 44 and 45 of the upper belt rollers. By depressing the lever arm 85, as shown in Fig. 2, the yoke is 90 lifted and with it the yoke arms and the arms 88 and 89. The rollers 37 and 38 and the upper feed belt 35 is thereby lifted. A flat bow spring 91 is provided to bear upon the arms 88 and 89 for the purpose of keeping the rollers 37 and 38 down and to maintain or increase the pressure between the upper and lower belts, and over the curved contact table 34 with the contained 95 moving print paper and tracings or negatives.

The belt 82 which receives the blue-print paper and negatives from the feeding apparatus extends about the end rollers 92 and 93 and the intermediate roller 94. The roller 92 is disposed beneath the bridging plate 81 and the belt 82 is made to assume a curvature about the glass convex exposure plate 95 within which are situated one or more lamps 96. The belt 82 advances the blue-print paper and negatives or tracings and also presses these superposed papers tightly against the glass exposure plate 95 as is required for clear and accurate printing.

Above the glass exposure plate 95 is an 115 apron 97 extending horizontally above the lamp station 96 and having the downwardly curved lip 98 pushed adjacent the belt 82. This lip and apron are intended to catch the uppermost tracing or negative after the 120 first exposure and to carry this tracing or negative off and into the hopper 99 disposed above the feeding apparatus. The blue-print paper, which has been previously threaded entirely through the machine as indicated in dotted lines at 100 then maintains the innermost negative or tracing in contact with the belt 82 and the two are driven up to the transposed or inverting device, which 125 device includes the curved contact table 101 130

and the upper and lower belts 102 and 103. The upper belt extends about the end rollers 104 and 105, and about the intermediate roller 106 while the lower belt extends about the rollers 107 and 108. The adjacent runs of both belts extend above and in contact with the convex or curved table 101 and the remaining tracing or negative and blue-print paper are intended to be received between the adjacent runs of such belts, the belts being driven as hereinafter explained, to feed the blue-print paper and tracing to the second or final exposure station. The contact table 101 and the belts 102 and 103 are all carried by a unit frame 109 pivoted about the center 110 which is the axis of the roller 93. This enables the frame 109 carrying all of the parts referred to to be swung outwardly as when cleaning curved exposing glass or the lamps. Pivoted directing plates 111 and 112 are placed at opposite ends of the transposing or inverting apparatus in order to bridge the gaps necessarily left between the bights of the rollers and to conduct the films or webs from one roll to another. The upper exposure station consists of the convex glass exposure plate 113 which is carried in the main frame above the first exposure station and its convexity extends in an opposite direction to the convexity of the first glass exposure plate 95. Behind the plate 113 are the lamps 114 and a belt 115 is used to feed the tracing and sensitized paper and to create pressure of the two against the plate 113. The belt 115 extends about the rollers 116 and 117 at the ends of the belt and about the intermediate roller 118. The second tracing or negative is carried off by an apron 119 and its lip 120 to a second hopper 121 disposed at the opposite side of the framework from the first-mentioned hopper. The blue-print paper indicated by the dotted line 100 is carried upwardly and over the rolls 122 and 123 carried upon suitable arms or brackets at the top of the machine; the blue-print paper being subsequently conveyed to a washing and drying apparatus.

Now the various rolls for the belts may be driven in any appropriate manner; for instance, by means of the arrangement of the gearing shown which is all taken off from the shaft 20. This shaft 20 is provided with a beveled pinion 124 shown in Fig 1 for meshing with a second beveled pinion 125 on a horizontal shaft 110. This shaft 110 is the shaft for the roll 93 and this roll and the belt 82 is driven through this train of connection. Power is also taken off from the shaft 20 by means of the beveled gear wheel 126 meshing with the companion gear wheel 127 on the horizontal shaft 128 which extends over the opposite side of the frame and is provided with the beveled pinion 129 disposed in mesh with the similar com-

panion pinion 130 on the vertical rod or shaft 131 which parallels the shaft 20. As shown in Fig 3 the shaft 131 at its upper end is provided with the pinion 132 arranged in mesh with the companion pinion 133 on the horizontal shaft 134 of the roll 117. This arrangement provides for driving the upper belt 115. The shaft 131 extends down to the feeding apparatus as shown more particularly in Fig. 4 where it is provided with the beveled pinion 135 meshing with the opposite pinions 136 and 137 and with the right-angularly disposed pinion 138 on the shaft 139 by which power is communicated through the beveled gear wheels 140 and 141 to the shaft 45 of the feed roll 38. The beveled gear wheel 137 is mounted on the stub shaft 90 having also the sprocket 142 over which extends the chain 143 indicated in Fig 5 by which power is conveyed to a lower sprocket wheel 144 on a shaft 145 which also drives the chain 146 whereby motion is communicated to the shaft 42 of the roll 40 for the lower feed belt.

Power is also taken off from the shaft 145 to drive the chain 147 which extends to a smaller sprocket on the shaft 26' to the lower feed chain whereby said lower feed chain is driven.

The pinion 136 shown in Fig. 4 is mounted on a stub shaft with a sprocket 148 for driving a chain 149 which also extends about a sprocket on a shaft 151 of the roller 23 for the upper feed chain. It is thus noted that the feed chains will be driven in opposite directions as required.

The transposing and inverting belts are driven from the shaft 110 of the roll 93 by means shown in Fig. 1. The shaft 110 and the shaft 152 are provided with sprockets to receive the chain 153 and shaft 152 is extended and provided with a pinion 154 meshing with another pinion 155 on the shaft 156 of the roll 107. Thereby both belts 102 and 103 are driven by power derived from shaft 110.

In operation, blue-print paper, having an emulsion upon both sides and contained in a roll is mounted within the casing 29 in the feed apparatus. This blue-print paper is attached with paste to a leader strip which is initially threaded through the entire machine and is brought out as shown by the dotted line 100 in Fig. 2. In order to get at this leader strip, the lever 85 shown in Fig. 2 may be depressed to raise the upper feed rollers and belt and enable the leader strip to be brought across through the feeding apparatus up to and engaged with the belt 82. After the leader strip is properly threaded through the machine, and the attached print paper is in motion through the contact table 34, the two tracings or negatives, which have been previously secured in the clamp bars by opening the jaws 53 and 54, are attached to the moving chains to register one above

the other. The machine is then in motion and the two registering clamp bars will pull the tracings or negatives along above the assembly table 21. Having reached the casing 29, the tracings will be drawn one above and one below such casing, so that after passing about the casing one tracing is above and the other tracing is below the web of the blue-print paper. Consequently, when these three superposed webs or films arrive opposite the first exposure station, the upper side of the blue-print paper will be printed from the uppermost negative or tracing. This tracing is thereafter removed from the machine and delivered to the hopper 99 while the blue-print paper and tracing that was initially lowermost is passed on upwardly and made to undergo a transposing or inverting movement by which the initially lowermost tracing or negative is brought uppermost and against the convex glass plate 113 at the upper exposure station thus bringing the parts into position for printing upon the opposite side of the blue-print paper of the matter on the second tracing. The second tracing is then delivered to the upper hopper 121 and the blue-print paper carried off as shown in dotted lines in Fig. 2 of the washing and drying stations.

As the registering bars return to the front of the assembly table they are automatically released by means of the stops 203 and 204 and drop into the hoppers 205 and 206.

If it is desirable to print a single sheet upon both sides, the leader strip is not fed through the machine, but a sheet of the sensitized double coated paper is cut off of the required size; the two tracings are attached to the registering bars and the sheet of cut paper attached to the power registering bar and on top of the tracings in which position the bars are attached to the chains which will advance them to the various positions, as above described, for the printing of the two tracings, one on either side of the paper.

For printing on one side of a continuous roll the frame 22 is lowered by means of the rack 200 and pinion 201 to such position that a board, not shown, may be placed across the frame 22 allowing the paper with its superimposed tracing to be fed direct to the belt 82.

From the above description it will be seen that by the use of these improvements a 100% utilization of the surface of the print paper is made when printing on both sides of such paper; that a continuous roll or single sheets may be printed; that a double or single printing may be accomplished; that it requires only one operator, and in the case of the double printing the product allows a large saving in the amount of paper used, storage space required for record prints, reduced cost in transportation, as well as other advantages.

The machine may be also used by inserting two single coated rolls with the uncoated surfaces in contact and then feeding the tracings as before which will increase the capacity of the present method of getting single coated blue prints 100%. 70

It will be obvious also that many other changes in the construction, combination and arrangement of parts could be made, which could be used without departing from the spirit of my invention, and I do not mean to limit the invention to such details, except as particularly pointed out in the claims. 75

Having thus described my invention, what I claim and desire to secure by Letters Patent of the United States is:

1. A blue printing machine comprising an assembly and feeding station for initially assembling two tracings and a sheet of blue print paper sensitized on both sides with the tracings on opposite sides of the blue print paper, an initial exposure station past which the two negatives and blue print paper are moved together for printing one side of the blue print paper from one of the tracings, and a second exposure station for receiving the blue print paper and other tracing for printing upon the opposite side of the blue print paper the contents of the second tracing. 95

2. A blue printing machine comprising an assembly and feeding station for disposing a negative upon each side of a sensitized blue print paper having an emulsion upon both sides thereof, an initial exposure station for receiving said superposed negatives and blue print paper and for exposing one side of the blue print paper to one of the negatives, means for subsequently carrying off the printed negative, and a second exposure station for exposing the opposite side of the blue print paper to the second negative. 100 105

3. A blue printing machine comprising an assembly and feeding station for disposing a negative upon each side of a sensitized blue print paper having an emulsion upon both sides thereof, an initial exposure station for receiving said superposed negatives and blue print paper and for exposing one side of the blue print paper to one of the negatives, means for subsequently carrying off the printed negative, and a second exposure station for exposing the opposite side of the blue print paper to the second negative, means for conveying off the second negative from the second exposure station, and means for conveying off the doubly exposed blue print paper separately. 110 115 120

4. A blue printing machine comprising an assembly and feeding station for introducing negatives in matching relation at opposite sides of a blue print paper having both sides sensitized, an initial exposure station for printing one side of the blue print paper

from one of the negatives, a holder for receiving the printed negative after passing through said initial exposure station, a transposing and inverting device for receiving the blue print paper and other negative, a second exposure station for receiving said other negative and blue print paper from the transposing and inverting device, and means for separating said other negative and 10 blue print paper after the second exposure.

5. A blue printing machine comprising an assembly and feeding station for bringing two tracings upon opposite sides of a doubly sensitized blue print paper, an initial exposure station for printing one side of the blue print paper from one of the tracings, a holder for receiving said printed tracings after passing through the initial station, a transposing and inverting device for receiving the blue print paper and other tracing from the first station, a second exposure station for receiving the blue print paper and other tracing from the transposing and inverting device, whereby to print the blue 20 print paper upon the opposite side, a holder for receiving the other tracing after passing through the second station, and means for separately carrying off the blue print paper.

6. A machine for making blue prints from tracings comprising a narrow vertical frame, exposure stations mounted one above another in said frame, a transposing and inverting device between said stations, receptacles at opposite sides of said stations for receiving the previously exposed tracings, means at the upper portion of the frame for carrying off the blue print paper separately from the tracings, a feeding mechanism, and an assembly mechanism for superposing the tracings upon opposite sides of the blue print paper.

7. A blue printing machine comprising a main frame, an initial exposure station on said frame having a convex plate, a source of illumination behind the plate, and a feed belt adapted to move over said plate, a second exposure station on the main frame above the initial station and composed also of a convex plate, an illuminating source behind the plate and a moving belt extending across the plate, said plate extending oppositely to the first mentioned plate, means for feeding to the initial plate and belt, a sheet of blue print paper with a tracing above and below the same, whereby to expose one side of the blue print paper to the respective tracing, means for carrying off the exposed tracing, means for inverting the blue print paper and second tracing and for delivering same to the second exposure plate and belt, and means for separating the second tracing and blue print paper after the second exposure.

8. A blue printing machine comprising a frame, an initial exposure station on said

frame, a final exposure station on the frame above the initial station, means for feeding to the initial station a blue print paper with tracings on opposite sides of same, means for removing beyond the initial station the 70 printed tracing, an inverting device for receiving the other tracing and blue print paper from the initial station and passing the same to the final station, said inverting device comprising a curved pressure plate 75 and belts having their adjacent runs on the convex side of said plate and being stretched tightly across said plate, the tracing and blue print paper adapted to be received between the adjacent runs of said belts.

9. A blue printing machine comprising a frame, an initial exposure station on said frame, a final exposure station on the frame above the initial station, means for feeding to the initial station a blue print paper with tracings on opposite sides of same, means for removing after the initial station the printed tracing, an inverting device for receiving the other tracing and blue print paper from the initial station and passing same to the final station, said inverting device comprising a convex pressure plate and belts moving in the same direction over the convex side of said plate and a hinged frame carrying said plate and belts and adapted to swing outwardly to deliver the blue print paper and tracing at a remote point from the final exposure station.

10. A blue printing machine comprising an exposure station, and means for feeding a blue print and tracing to the exposure station comprising an assembly table, means for moving the tracing over said table, means for holding a blue print paper to be placed alongside said tracing, and feeding means in advance of the exposure station for pressing and advancing said superposed tracing and blue print paper.

11. A blue printing machine comprising an exposure station, and means for assembling and feeding a superposed tracing and blue print paper to the station comprising a movable chain, means attachable to the chain for clamping and drawing the tracing therealong, means for holding the blue print paper adjoining the chain, whereby the blue print paper may be drawn out against the tracing and pressure and feeding means for pressing the blue print paper and tracing tightly together and advancing same to the exposure station.

12. A blue printing machine comprising an exposure station, pressure feeding belts adjoining said station, means for moving said belts, a blue print roll adjoining the belts and means for drawing two tracings in opposite directions about said blue print roll and upon opposite sides of the blue print paper issuing from said roll.

13. A blue printing machine comprising

- an exposure station, a pair of feeding belts having their adjacent runs moving in the direction toward said exposure station; a curved pressure plate bearing against said adjacent runs of the belt for placing them under tension, a blue print roll adjacent the belts, and movable means for drawing two tracings along and upon opposite sides of said blue print roll and for drawing the tracings through the belts on opposite sides of the blue print paper issuing from said roll, and means for detaching the tracings from said last named means. 45
14. A blue printing machine comprising an exposure station, a pair of feeding belts adjoining said station, a blue print roll adjoining the feeding belts, endless driven chains, means carried by said chains for drawing two tracings in the same direction about the blue print roll and through said feeding belts upon opposite sides of the blue print paper, while the belts subject the tracings and paper to pressure for feeding the blue print paper along, and means for disengaging said last named means. 50
15. A blue printing machine comprising an exposure station, pressure and feeding belts adjoining said station, a blue print roll adjoining the belts, endless driven chains extending about said roll and about said feeding belts, clamp bars removably attached to said chains for grasping and drawing tracings along with the chains and to opposite sides of the blue print paper and through said feeding belts, and means for automatically disengaging the tracings from said clamp bars. 55
16. A blue printing machine comprising an exposure station, pressure means adjacent the station, tracing feeding means, a blue print roll extending between said tracing feeding means, said tracing feeding means including clamp bars composed of openable jaws for grasping the tracings and relatively movable parts for opening and closing said jaws, and means for automatically opening said jaws when the tracings have arrived adjacent the exposure station. 60
17. A blue printing machine comprising an exposure station, pressure means adjoining the station, tracing feeding means, a blue print roll between said tracing feeding means adjoining said pressure means, clamp bars removably carried by said tracing feeding means and having spring jaws for receiving the tracings, said bars being composed of inner movable cores and outer relatively fixed shells, said cores and shells having troughs and crests arranged therebetween for opening and closing the jaws on axial shifting movement of the cores and means for automatically shifting said cores. 65
18. A blue printing machine comprising an exposure station, a blue print roll, endless chains upon opposite sides of said roll and having sockets therein, clamp bars adapted to be selectively attached to said chains and composed of outer resilient shells and inner axially movable cores having the ends detachably fitted in said sockets, clamp collars 70 on said cores, fixed cam abutments for engaging said collars to shift said cores and for holding said shells against movement, and resilient means to hold said cores in initial position. 75
19. A blue printing machine comprising an exposure station, a pair of feeding belts adjoining the station for receiving tracings and blue print paper, a curved contact table for bearing upon the adjacent runs of the belts, means for positively drawing the tracings through the belts, a movable plate near the delivery end of said belts, resilient means for holding said plate in an initial position, and means for automatically sliding said plate toward the exposure station. 80 85
